UNITED STATES PATENT OFFICE.

GEORGE C. RICKLY, OF OTTAWA, ILLINOIS.

TOBACCO-PIPE.

1,072,167.

Specification of Letters Patent. Patented Sept. 2, 1913.

Application filed August 3, 1909. Serial No. 510,976.

To all whom it may concern:

Be it known that I, GEORGE C. RICKLY, a citizen of the United States, and a resident of Ottawa, in the county of LaSalle and 5 State of Illinois, have invented certain new and useful Improvements in Tobacco-Pipes, of which the following is a full, clear, and exact specification.

My invention is concerned with pipes for 10 smoking tobacco, and is designed to produce a pipe that shall have ample draft that can readily be maintained without removing the mouthpiece or resorting to the use of special cleaning tools, and which more especially 15 will enable me to have a cool smoke of the entire contents of the pipe and without danger of its becoming clogged.

In carrying out my invention, I employ a 20 plurality of passages, preferably two, either of which alone would be too small for a free draft and would tend to clog, while both furnish an ample draft and neither of them is so large as to permit the tobacco to be drawn into it. I locate the upper passage 25 at such an angle that if it should accidentally become clogged up, it can be cleared out by a wooden toothpick, or some similar article, inserted from the top of the bowl.

To illustrate my invention, I annex hereto 30 a sheet of drawings, in which the same reference characters are used to designate identical parts in all the figures, of which,—

Figure 1 is a longitudinal section through the bowl and stem; and Fig. 2 is an end 35 elevation.

The bowl *a* and the stem *b* may, so far as 40 the exterior is concerned, be of the customary construction, as well as the mouthpiece *c*, which fits into the main tapered passage *d* in the stem. The two passages *e* and *f* from the bowl into the main passage *d* are, as shown, preferably of substantially the same area in cross-section, and neither of them is 45 large enough to furnish as free a draft as desired, but both of them together furnish an abundant draft. Neither of them is large enough to permit the tobacco to be drawn through the passages into the stem and mouthpiece. I employ in connection with

50 my present invention the valve *g*, which is shown and described in my prior Patent No. 574,495, and the lower passage *f* opens into the bottom of the bowl opposite to the valve. As shown, the upper passage *e* is set at an 55 angle of, say, sixty degrees to the other pas-

sage *f*, and it will be noted that it extends at such an angle that a wooden toothpick or some similar article can be inserted from the top of the bowl to clear the passage out, and the main passage *d* extends far enough in 60 so as to produce the angle *h* in a position to form a continuation, as it were, of the passage *e*.

In the use of an ordinary pipe, such as would be represented by my pipe herein 65 illustrated without the valve *g* and the passage *e*, it will be apparent that all the air drawn through the stem must pass through the burning tobacco in the bowl, with the result that the tobacco burns too fast and 70 the air is too hot to be drawn into the mouth with comfort. To overcome these difficulties, I devised the novel apparatus shown in my Patent No. 574,495, which employs a valve of the general character of that shown at *g* 75 in my present application, and having the same location and mode of operation. While the employment of this valve overcame the objections above noted by drawing some of the air through the valve *g*, and consequently less of it through the burning tobacco, it developed the difficulty that the bottom of the bowl was kept so cool that the moisture or water formed by the burning of the tobacco condensed or was deposited in the bottom of the bowl sufficiently 80 so that the tobacco at the bottom was moistened enough to cause it to clog the opening *f*, thus interfering with the smoking. To remedy this difficulty, I have added the extra passage *e*, through which much of the smoke and vaporized water is drawn, thus largely removing the tendency, which would otherwise exist, of the moisture to collect at the bottom of the bowl and moisten the 85 tobacco enough to stop the passage *f*. When the tobacco burns below the upper end of the passage *e*, the heat is so close to the bottom of the bowl that the moisture cannot condense there, as it is too hot, and, as a 90 result, I can smoke the pipe clear to the bottom without the moisture being deposited so as to tend to clog either opening.

What I claim as new, and desire to secure by Letters Patent of the United States, is: 105

A pipe consisting of a bowl and stem having two simultaneously open passages leading from the bowl to the stem, the lower passage opening near the bottom of the bowl and the upper one near the center, the 110

cross-sectional area of the passages being small enough to prevent the tobacco from being drawn thereinto, while the combined area is large enough to give an ample draft, 5 a valve-opening in the bowl at substantially the bottom thereof to permit some cool air to be drawn therethrough and mixed with the hot gaseous products of combustion, and a mouthpiece terminating short of the open-

ings of the two passages into the stem, substantially as and for the purpose described. 10

In witness whereof, I have hereunto set my hand and affixed my seal this 28th day of July, A. D. 1909.

GEORGE C. RICKLY. [L. S.]
